STAND FOR COOKING VESSELS

Margarete Hendel, Leipzig, Germany; vested in
the Alien Property CustodianApplication October 24, 1940, Serial No. 362,559½
In Germany October 17, 1938

1 Claim. (Cl. 126—214)

This invention relates to a stand for supporting cooking vessels on cooking apparatus equipped with a burner and operated by a flame produced by gas, etc., and has for its object to provide a stand of a type capable of preventing accidents due to the extinction of the flame by overflowing cooking material and the consequent outflow of gas, etc, and also soiling of the burner.

The stand according to the invention substantially comprises two preferably conical rings arranged one within the other on different levels and interconnected by bridges, so that the flame can pass between the rings and heat also the sides of a vessel placed on the stand thus formed. Having a free outlet, the flame is moreover fanned by the air in a particularly favorable manner.

Compared with the known devices of this class, the stand according to the invention affords the advantage that the flame is not held back by the bottom of the vessel to be heated and that owing to the arrangement of the outer ring supporting the vessel and acting as screening member on a higher level than the inner ring overflowing or spilled material is absolutely prevented from splashing inwardly and reaching the burner.

One form of the invention is illustrated in the accompanying drawing, in which

Fig. 1, a partial view of a stand according to the invention for supporting a vessel placed on the top thereof;

Figs. 2 and 3 are partial views of modifications of the stand shown in Fig. 1;

Fig. 4 is a section of Fig. 2; and

Fig. 5 is a section of Fig. 3.

The stand shown in Figs. 1 to 5 comprises two preferably conical rings, the outer ring 13 or deflecting member being positioned slightly higher than the inner ring 14, and the outer ring being arranged to rest upon the stove top around the burner opening as shown in Figure 4; or the inner

ring being provided with slots 18 to receive the bars 18' of the stove top as shown in Figure 5, whereby the stand is supported on the cooking apparatus. Both rings 13, 14 are connected on top by preferably angular bridges 15 which have flat upper surfaces assisting in supporting a vessel. The flame sweeping outwardly between the two rings 13, 14 is fanned by the air current and heats also the sides of the vessel. The outer ring 13 may also have a flat top.

As indicated in Figs. 2 and 4, the inner ring 14 may be downwardly extended to form a cylindrical screening member 16 which surrounds the burner and thus affords increased protection. In this case, the stand rests with its outer ring 13 on the cooking apparatus.

In the construction shown in Figs. 3 and 5 the inner ring 14 is also made broader and surrounds the burner like a funnel. In its screening wall 17 the ring 14 is provided with slots 18 for engaging the bars 18' of the burner opening.

What is claimed is:

A detachable stand for a gas or similar burner, said stand comprising outer and inner substantially concentrically spaced rings, the upper edge of the outer ring being arranged to supportably engage the bottom of a cooking vessel or the like being heated over the burner, the inner ring having its upper edge depressed below the upper edge of the outer ring, circumferentially spaced angle brackets spacing and connecting the inner and outer rings with lateral arms of the brackets joined to the outer ring adjacent to its upper edge and with the lower extremity of the vertical arms of the brackets joined to the upper edge of the inner ring, the lower part of said inner ring surrounding the burner in a manner to protect the burner from material overflowing from the cooking vessel.

MARGARETE HENDEL.
